APPARATUS FOR ELECTRICAL USES

Erwin E. Franz, Cranford, N. J., assignor to
Western Electric Company, Incorporated, New
York, N. Y., a corporation of New York

Application May 10, 1934, Serial No. 724,925

7 Claims. (Cl. 29—84)

This invention relates to laminated articles and a method of and apparatus for making them, and more particularly to laminated cores for electrical and magnetic apparatus and a method 5 of and apparatus for assembling the cores and adjusting them in electrical apparatus.

In the manufacture of electro-magnetic apparatus particularly, such as induction coils and the like in which one or more electrical conductors are wound upon or coiled and placed upon a core of magnetic material it is often advantageous to have the core built of laminar units of magnetically highly permeable material such as certain recently discovered alloys of nickel and iron 10 or of nickel, chromium and iron which are unusually permeable after proper heat treatment. Such alloys, however, are extremely sensitive and lose permeability to a marked degree when subjected to only small degrees of cold working such as bending or twisting or even compression. In 15 some instances cores built up of laminae of such material have been fastened together with mechanically compressive clips, or with rivets or bolts, or other analogous means which impose more or less stress upon and thereby induce some 20 strain in the material thus tending to adversely affect the permeability.

An object of the present invention is to provide a method of and apparatus for making cores of permeable alloys and assembling them in electrical apparatus in which no stress upon or strain in the material is produced thus tending to maintain their high permeability unimpaired.

With the above and other objects in view one embodiment of the invention comprises stacking a file of core laminations together, applying a viscous adhesive substance to the congruent edges of the laminations and letting the adhesive dry. Two such assemblies of laminations which are then sufficiently coherent to be handled gently 35 without disruption, may then be placed in position in or/and around one or more preformed coils of conductor strands with or without a supporting spool of dielectric material. A supply of adhesive material may be placed between juxtaposed parts of the two laminated core stacks. A testing instrument may then be connected to the coiled conductors to test some electrical characteristic of the coil such as self inductance, inductive coupling between coils, or the like, which 40 is a function of the permeability of the magnetic circuit through the two core parts. The latter may then be adjusted to a desired predetermined value by approximating or separating the two core stacks thus altering the air gap between 45

them. When the desired value is attained the whole assembly is held lightly but rigidly in place until the adhesive between the core stacks dries. Thus a core is produced and assembled in electrical apparatus of accurately predetermined magnetic reluctance while preserving the magnetically sensitive material of the core from any impairment. Means are also provided to hold the core halves immovably apart while the interposed adhesive material is drying since such material ordinarily shrinks while setting and would tend to draw the core halves together if they were free to move thus altering the carefully made and sensitively adjusted magnetic circuit.

Other objects and features of the invention 15 will appear from the following detailed description of one embodiment of the invention taken in connection with the accompanying drawing in which like reference numerals are applied to identical parts in the several figures and in which 20

Fig. 1 is a perspective view of an inductance coil embodying the invention;

Fig. 2 is a view of such a coil in central longitudinal section, the coil being held in an assembly and adjustment device; and

Fig. 3 is a broken perspective view of a completed half core.

In the embodiment of the invention herein disclosed, an inductance coil comprises two half cores 21 and 21 of magnetic material, a spool 22 of dielectric material mounted on the cores 21, 30 and two conductors 23 and 24 wound on the spool.

The two half cores 21 are identically alike in shape and are symmetrically juxtaposed in the assembled coil. Each half core comprises a plurality of flat E shaped laminae 25 punched or otherwise formed from a sheet of highly magnetically permeable alloy such as certain well known alloys of iron and nickel known generally as "permalloy" and containing in one case, for 40 example, 17.7% iron, 78.5% nickel and 3.8% chromium. These alloys are highly sensitive to mechanical stresses and strains, especially when in their condition of maximum permeability which is attained by heat treatment.

The laminae 25 after being formed are heat treated to produce maximum magnetic permeability therein, the specific alloy above mentioned being annealed at about 1980° F. for an hour and cooled slowly. The laminae are then 50 magnetically highly permeable and so sensitive that even slight accidental cold working or jar-ring will decrease the permeability by a quarter or even a third or more.

In some instances such laminae in the past 55

have been appropriately perforated before the heat treatment and after being treated have been filed in stacks and fastened together by means of rivets passed through the perforations. 5 It is extremely difficult, however, to fasten the rivets or other means tightly in place without some deformation of at least the two or three external laminae on each side of the stack with consequent loss of permeability. However, in 10 some cases it is not necessary that the laminae be strongly held together. Hence in accordance with the present invention the block of heat treated and stacked laminae is coated on one or more peripheral faces formed by the edges of 15 the laminae with a viscous and relatively quick-drying cement. A solution or dispersion of a cellulose product in a solvent such as acetone or trichlorethane or the like has been found satisfactory for this purpose. The cement is preferably sufficiently thick and viscous not to be 20 drawn in between the laminae by capillary attraction, but to remain on and adherent only to the edges of the laminae.

It is found that a block of metallic laminae thus held together is sufficiently well united to be 25 transported and manipulated as a self coherent unit satisfactorily, especially if the adhesive coating be applied to at least two mutually perpendicular faces of the block. Such a block is separately illustrated in Figure 3, in which the 30 laminations are indicated at 25 and the adhesive coating 26 is applied to three faces of the block of laminae.

In the illustrative example herein disclosed, 35 the spool 22 and its windings 23 and 24 are assembled as a unit before being combined with the two core halves 21. The spool consists of a central sleeve 27 on the outside of which the windings 23 and 24 are placed, spacing flanges 40 28, 29 and 30 which serve to confine the windings and an internal transverse septum 31. The sleeve 27, flanges 28, 29 and 30, and the septum 31 are integral and the whole is preferably molded from a moldable dielectric material such as hard rubber, artificial resin, cellulose acetate, 45 or the like, although the precise nature and form and material of the spool are no part of the invention.

With the parts as shown, the core halves are 50 assembled with the wound spool by inserting the central tongue 32 of each core half into the ends of the sleeve 27 and means are preferably provided to retain the cores in place. According to the invention this means comprises masses 55 33 of adhesive material like that used for the coating 26 placed in the bottoms of the two pockets formed within the sleeve 27 by the septum 31.

There are two distinct relative adjustments of the two half cores and of the wound spool thus 60 assembled which are of importance; the adjustment of the air gap between the half cores to obtain a predetermined total reluctance of the magnetic circuit and the adjustment of the core as a whole within the spool to obtain a predetermined value of the mutual inductance of the two windings.

To effect these two adjustments conveniently and accurately the apparatus shown in Figure 2 is provided. This apparatus comprises a base member 40 generally rectangular in outline and generally of a troughlike form. An adjusting screw 41 is mounted centrally and longitudinally therein and provided with a knurled head 42. A cradle 43 is slidable longitudinally in the 70 trough and is perforated and threaded to coat

with and be adjustable in position by the screw 41. The cradle has two upstanding parallel lugs 44 adapted to receive and hold the spool 22 which fits snugly between them. A post 45 is secured to or integral with the rear of the base member 40 and carries a generally C shaped clamp 46 extending over the trough of the base. The clamp 46 is formed and proportioned to receive between its resilient ends a pair of core halves and to urge them gently together as shown. 10

A second adjusting screw 47 is also mounted in the base member 40 transversely thereof and has a knurled head 48. Two opposed and coacting wedges 49 and 50 are mounted in the base member with freedom to slide transversely thereof, and are perforated and threaded to coat with the screw 47 to be driven thereby. The screw 47 is oppositely threaded at its two ends and so acts to draw the wedges together when turned one way and to drive them apart when turned the other way. These wedges are so positioned and proportioned as to enter between the adjacent opposed arm ends of two core halves as shown. 15

In operation a spool 22 having windings 23 25 and 24 thereon has a mass of adhesive material 33 placed in each of its central pockets. Two core halves 21 are then juxtaposed in and on the spool with their central arms 32 positioned in the central pockets of the spool. The spool and 30 the two core halves thus assembled are then placed in position in the adjusting apparatus as shown in Figure 2 and a testing circuit is connected to the ends of the windings 23 and 24. Since such testing circuits and the devices 35 included therein are well known, of many kinds, and form no part of the present invention, the circuit is not disclosed here.

By manipulation of the knurled head 48, the two core halves 21 may be driven apart by the 40 wedges 49 and 50 or allowed to approach each other under the urge of the spring 46 until the reluctance value of the magnetic circuit required is attained. Then by manipulation of the knurled head 42, the spool 22 with its windings 23 and 24 may be adjusted longitudinally of the core until the mutual inductance of the windings takes on its desired value. The whole is then allowed to rest until the adhesive masses 33 are thoroughly dry and have attained a substantially final state of invariable volume and form. 45

During this drying or setting of the adhesive masses 33, they tend to contract and draw the core halves together and thus tend to close the air gap between the core halves and change the 50 adjusted value of the reluctance of the magnetic circuit. They also may shrink unequally thus tending to shift the spool on the core as a whole which would tend to disturb the adjusted value of the mutual inductance of the windings. The 55 tendency of the adhesive to draw the core halves together is resisted by the positive and immovable wedges interposed therebetween, and the tendency of the adhesive to shift the spool on the cores is resisted by the positive and immovable grip of the lugs 43 and 44 on the spool.

Thus the spool with its windings and the two core halves are held immovably in their adjusted relative positions until the adhesive is set and has become an unchanging unifying element in the 60 whole assembly. The finished coil is then removed from the apparatus and has and maintains the desired electro-magnetic property values.

The embodiment of the invention herein dis- 75

closed is illustrative merely and may be modified and departed from in many ways without departing from the spirit and scope of the invention as pointed out in and limited solely by the 5 appended claims.

In particular it may be pointed out that the 10 septum 31 is not an essential feature, nor in fact is the spool as a whole. If the windings 23 and 24 were placed directly on the core with adhesive material between the windings and the 15 core and means were provided to adjust the core halves relatively to each other and to adjust the windings on the core and to hold the core halves and the windings relatively immovable in positive 20 fashion until the adhesive between the core halves and between the core and the windings were permanently set, the essence of the invention would still be present. It may also be pointed out that the means such as the wedges 49 and 50 to hold the core halves apart must be positive since the tendency of the adhesive 33 in drying and setting is to shrink and draw the core halves together. Spring means instead of wedges or other positive means will not do. On 25 the other hand spring means to hold the core halves together are sufficient although a positive means might equally well be used.

What is claimed is:

1. The method of manufacturing electrical 30 apparatus which comprises juxtaposing two magnetic core members with adhesive material therebetween, adjusting the magnetic gap between the members until predetermined electrical properties are obtained, and positively 35 holding the core members against approach to each other until the plastic adhesive material has permanently set.

2. The method of manufacturing electrical 40 apparatus which comprises juxtaposing two magnetic core members with adhesive material therebetween, assembling therewith a third member with plastic adhesive material therebetween, adjusting the magnetic gap between the core members and adjusting the position 45 of the third member relative to the core members until predetermined electrical properties are obtained and positively holding the three members against approach to each other until the plastic adhesive material has permanently set.

3. The method of manufacturing electrical coils which consists in placing a winding on a

divided core, positioning adhesive material between the ends of the core which provides an air gap between the core sections, adjusting the air gap with the adhesive material in a plastic state until predetermined electrical properties 5 are obtained, and holding the whole positively against the contractive effect of the adhesive material while drying until the adhesive material has permanently set.

4. The method of manufacturing electrical 10 apparatus having magnetic cores of unstressed laminae construction which comprises stacking together laminae of magnetic material into a block, applying adhesive material to a surface of the block formed by the edges of a plurality 15 of the laminae, allowing the adhesive material to permanently set, assembling two such blocks together with a winding, positioning a second supply of adhesive material between the two blocks and between the blocks and the winding, 20 adjusting the relative positions of the two blocks and of the winding until predetermined electrical properties are obtained, and positively holding the two blocks and the winding in relative position against the contractive effect of the 25 drying adhesive material until the second adhesive material has permanently set.

5. In an apparatus for assembling electrical 30 devices having a two part core and a winding thereon, means to press the two parts of the core together, positive mean to force the two parts of the core apart, and means to positively adjust the position of the winding relative to the core parts.

6. In an apparatus for assembling electrical 35 apparatus having a two part core and a winding thereon, means to adjust the two parts of the core positively with respect to each other and to hold them positively in their adjusted position against approach to each other, and means to 40 positively adjust the winding in position with respect to the core parts and to hold the same immovably in its adjusted position.

7. In an apparatus for assembling electrical 45 apparatus having a two part core with adhesive material between the parts thereof, means to adjust the two parts of the core positively with respect to each other while the adhesive material is soft and to hold the core parts positively in their adjusted position against approach to each 50 other while the adhesive material sets.

ERWIN E. FRANZ.
